BRASSIÈRE

Maurice Berk, Hackensack, N. J.

Application December 6, 1940, Serial No. 368,778

6 Claims. (Cl. 2—42)

This invention relates to new and useful improvements in brassières and the like.

More specifically the invention contemplates a brassière having a brassière body of substantially nonstretchable cloth material formed with brassière pockets at the front which have substantially triangularly shaped openings extended inwards from the bottom edges thereof with their apexes at the nipple portions of the pockets, and novel arrangement of one way stretch gussets set into said openings in a particular way to increase the uplifting and supporting effect of the brassière.

More specifically, the invention contemplates arranging the gussets so that the material thereof is stretchable crosswise of the brassière body.

Still further the invention proposes the provision of non-stretchable tapes attached on said gussets and extending from the apexes to the opposed sides for reinforcing these areas to increase the supporting effect of the brassière body.

Still further the invention proposes a modification in which the non-stretchable tapes are cooperative with non-stretchable straps extending across the triangular shaped openings in a manner so that the tapes may be fixedly held in any one of various positions to change their points of support of the breasts.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a front elevational view of a brassière constructed in accordance with this invention.

Fig. 2 is an enlarged sectional view taken on the line 2—2 of Fig. 1.

Fig. 3 is a fragmentary enlarged sectional view taken on the line 3—3 of Fig. 1.

Fig. 4 is a fragmentary front elevational view similar to a portion of Fig. 1 but illustrating a modified construction.

Fig. 5 is a fragmentary horizontal sectional view taken on the line 5—5 of Fig. 4.

The brassière or the like garment, in accordance with this invention, includes a brassière body 10 of substantially non-stretchable cloth material having breast pockets 11 at the front which have substantially triangular shaped openings 12 extended inwards from the bottom edges thereof, with their apexes at the nipple portions of the pockets. Substantially triangular shaped gussets 14 of one way stretch material are set into the triangular shaped openings 12 to stretch crosswise of the brassière body for engaging against the bottom portions of the breasts to resiliently uplift and support them. Tapes 15 of

non-stretchable material are attached on the gussets 14 and extend from the apexes to the opposed sides for reinforcing these areas to increase the supporting effect of the brassière body.

The brassière body 10 is constructed of the usual material with the usual trimmings. It is provided with the customary shoulder straps 16'. The gussets 14 are of heavy elastic web material. They are attached to the bottom portions of the pockets 11 by lines of stitches 16 extending along their sides. The tapes 15 are attached to the gussets 14 by stitches 17 extending along their lengths.

When the brassière is worn the one way stretch material of the gussets 14 extends crosswise beneath the breasts uplifting and supporting them and adding to the supporting action of the brassière body. The tapes 17 extend centrally forwards and rearwards along and underneath the breasts acting as a firm support.

In Figs. 4 and 5 a modified form of the invention has been disclosed which distinguishes from the prior form in that it embodies an adjustable arrangement of the tapes 15'. In accordance with this form of the invention, the tapes 15' may be extended laterally in one direction or the other from the apexes of the gussets 14. More specifically non-stretchable straps 18 extend crosswise of the triangular shaped openings 12 at the bottom edge of the brassière body. Each strap 18 is fixedly mounted at one end with stitches 19. The other ends of these straps are provided with fastening elements 20 selectively cooperative with a plurality of complementary fastening elements 21 located on the opposed sides of the openings 12 by which the straps 18 may be slackened or drawn tight as desired. A plurality of fastening elements 22 are arranged intermediate the lengths of the straps 18 and are selectively cooperative with complementary fastening elements 23 upon the ends of the tapes 15.

As illustrated in Fig. 4 the tape 15' is shown extended centrally of the cut out opening 12. If desired the tape 15' may be arranged to one side or the other of the central position, by disconnecting the fastening element 23 from the attached fastening element 22 and reconnecting the fastening element 23 with a different one of the fastening elements 22. For example, the dot and dash lines 15x illustrate the tape 15' in a position towards the left. The straps 18 are slackened or drawn in, as needed to permit the connection between selected fastened elements 22 and the fastening elements 23.

In other respects this form of the invention is similar to the previous form and like parts are identified by like reference numerals.

While I have illustrated and described the preferred embodiments of my invention, it is to be understood that I do not limit myself to the

precise constructions herein disclosed and the right is reserved to all changes and modifications coming within the scope of the invention as defined in the appended claims.

Having thus described my invention, what I claim as new, and desire to secure by United States Letters Patent is:

1. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom portions of the breasts to resiliently uplift and support them, and non-stretchable tapes each extending from the apex of its gusset to a point of the opposite side thereof and attached thereto at said apex and such point for reinforcing these areas to increase the supporting effect of the brassière body.

2. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom portions of the breasts to resiliently uplift and support them, and non-stretchable tapes each extending from the apex of its gusset to a point of the opposite side thereof and attached at its ends thereto for reinforcing these areas to increase the supporting effect of the brassière body, said gussets being set into said triangular shaped openings by their sides being sewed to the side portions of the openings.

3. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom portions of the breasts to resiliently uplift and support them, and a non-stretchable tape attached on each of said gussets and extending from the apexes to the opposed sides for reinforcing these areas to increase the supporting effect of the brassière body, said tapes being secured along their lengths with stitches to said gussets.

4. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom

portions of the breasts to resiliently uplift and support them, a non-stretchable tape extending upwardly across each of said gussets from the apexes to the opposed sides thereof for reinforcing these areas to increase the supporting effect of the brassière body, said tapes being attached at their apex ends to the apex portions of said gussets, and non-stretchable straps extending crosswise of said triangular shaped openings and provided with fastening elements cooperative with complementary fastening elements on the free ends of said tapes for holding said tapes in various angular positions.

5. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom portions of the breasts to resiliently uplift and support them, a non-stretchable tape extending upwardly across each of said gussets from the apex to the opposed side thereof for reinforcing these areas to increase the supporting effect of the brassière body, said tapes being attached at their apex ends to the apex portions of said gussets, and non-stretchable straps extending crosswise of said triangular shaped openings and provided with fastening elements cooperative with complementary fastening elements on the free ends of said tapes for holding said tapes in various angular positions, each of said non-stretchable straps being fixedly attached at one of its ends to one of the sides of its opening, and adjustably attached at its other end to the other side of its triangular opening.

6. A brassière or the like, comprising a brassière body of substantially non-stretchable cloth material, having breast pockets at the front which have substantially triangularly shaped openings extended inward from the bottom edges thereof with their apexes at the nipple portions of said pockets, triangularly shaped gussets of one way stretch material set into said triangularly shaped openings to stretch crosswise of said brassière body for engaging against the bottom portions of the breasts to resiliently uplift and support them, a non-stretchable tape extending upwardly across each of said gussets from the apex to the opposed side thereof for reinforcing these areas to increase the supporting effect of the brassière body, said tapes being attached at their apex ends to the apex portions of said gussets, and non-stretchable straps extending crosswise of said triangular shaped openings and provided with fastening elements cooperative with complementary fastening elements on the free ends of said tapes for holding said tapes in various angular positions, each of said non-stretchable straps being fixedly attached at one of its ends to one of the sides of the opening, and adjustably attached at its other end to the other side of said opening, said adjustable attachment comprising fastening elements on the non-stretchable straps cooperative with fastening elements on the material of the brassière body.

MAURICE BERK.
